(57) **CLAIM**

The ornamental design for a shower wall hair catcher, as shown and described.

DESCRIPTION

FIG. 1 is a front and top perspective view of a shower wall hair catcher, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof, shown in an alternative position.

The broken lines in the figures illustrate portions of the shower wall hair catcher that form no part of the claimed design.

1 Claim, 8 Drawing Sheets
